I. P. WENDELL.
CAR BRAKE SHOE.

No. 69,377.

Patented Oct. 1, 1867.

Inventor,

Isaac P. Wendell

UNITED STATES PATENT OFFICE.

ISAAC P. WENDELL, OF PHILADELPHIA, PENNSYLVANIA.

IMPROVEMENT IN CAR-BRAKE SHOES.

Specification forming part of Letters Patent No. 69,377, dated October 1, 1867.

To all whom it may concern:

Be it known that I, ISAAC P. WENDELL, of the city and county of Philadelphia, and State of Pennsylvania, have invented a new and useful Improvement in Brake-Shoes for Railroad-Cars; and I do hereby declare that the following is a full and exact description thereof, reference being had to the accompanying drawings, and to the letters of reference marked thereon.

My improvement, in the first place, consists in combining, with a cast-iron brake-shoe, wood, vulcanized rubber, or other similar material, to increase the binding capacity of the shoe; secondly, in a peculiar mode of connecting the shoe with its seat-stock, as will be understood by the following description.

Figure 1 is a face view of the improved shoe and parts in connection therewith. Fig. 2 is an edge view of the same. Fig. 3 is a vertical section of the same. Fig. 4 is a perspective view of the locking-bolt E.

Like letters in all the figures indicate the same parts.

A is a cast-iron shoe, having its face *a* curved to fit the wheel. Through the face there is a groove, in which I insert a piece of hard wood, B, with the end of the grain to the face. Projecting from the bottom of the groove is a stout pin or stud, *b*, which fits tight in the piece B, to prevent lateral movement of the latter, and to hold said piece firmly against the bottom of the groove, to obviate the necessity of its binding hard upon the edges of the same, which would have the tendency of springing the shoe.

C C are pieces of india-rubber, which are inserted in recesses *c c* in the face of the shoe. Instead of india-rubber, other similar material may be used.

The fillings B and C C cause a suction, and consequently give increased effectiveness to the shoe. Their arrangement may be modified as experience may dictate, so as to have more or fewer pieces inserted in the shoe; or they may all be constructed of wood, or all of rubber, as may be found most advantageous.

Instead of running the piece B clear across the shoe, it may only fill a mortise or recess, like those for the fillings C C.

Projecting from the back of the shoe A is a tongue, *d*, which lies in the circular groove *e*

of the seat-stock D, in which it has a partial turn, to allow of the rocking of the shoe, so as to accommodate its face to the face of the car-wheel.

At each end of the tongue there is a journal, *f*. The journals have clamping-caps *g g*, which confine the tongue in the groove.

The shoe is also connected or locked to the seat by means of the key-bolt E, which passes through the cheeks *h h*, which form the groove *e*, and through the tongue *f*. The said bolt keeps the shoe firmly in its longitudinal position and takes the main strain off the caps *g g*.

Although the round form of the bolt is the most suitable, yet it will answer in any other form by having the cross grooves or openings to correspond.

The key has a lug, *i*, which is passed through the groove *j*, and the key is then turned partly around until the arm *k* rests against the lug *l* on the side of the seat-stock D. The weight of the arm prevents the key turning back by any motion of the car, and consequently there is no danger of the shoe being disconnected from the seat-stock.

The stock is hung to the stirrups of the truck by means of a similar bolt, E'.

Having thus described my invention, what I claim therein as new, and desire to secure by Letters Patent, is—

1. The combination, with a cast-iron brake-shoe for railroad-cars, of pieces of wood, india-rubber, or other suitable material softer than the iron, substantially in the manner hereinbefore described, and for the purpose above specified.

2. The combination of the shoe A and stock D, by means of the groove *e*, tongue *f*, and cross-key E, substantially in the manner described, and for the purpose set forth.

3. The combination of the lug *i* and arm *k* with the keys E and E', substantially as described, and for the purpose specified.

In testimony that the above is my invention I have hereunto set my hand and affixed my seal this 19th day of December, 1866.

ISAAC P. WENDELL. [L. S.]
